UNITED STATES PATENT OFFICE.

JOHN J. BRESNAN, OF NEW YORK, N. Y., ASSIGNOR OF ONE-THIRD TO
SIMON BRENTANO, OF SAME PLACE.

HOSE-HOIST.

SPECIFICATION forming part of Letters Patent No. 351,160, dated October 19, 1886.

Application filed February 27, 1886. Serial No. 193,525. (No model.)

To all whom it may concern:

Be it known that I, JOHN J. BRESNAN, a citizen of the United States, residing at New York, in the county of New York and State of New York, have invented certain new and useful Improvements in Hose-Hoists; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

Hitherto in the use of firemen's hose much difficulty has been experienced in hoisting hose upon the roofs of buildings, or up to other elevations, to enable the firemen to direct the stream to advantage. The usual method is to carry a hoisting or roof line up to the roof or other elevation, and then to let the line down and attach it to the end of the hose, which is then drawn up by the line. The hoisting or roof line, which is one of the permanent appliances of a fire-department station, is of a sufficient length (usually from one hundred to one hundred and fifty feet) to reach the roofs of the highest buildings, and the hose, which is to be drawn up, must also necessarily reach from the roof to the ground. Such a length of hose is very heavy, and in hoisting it it must necessarily be either lifted bodily up or else drawn over the cornice of the roof. To sustain the strain which is thus put upon the hose a heavy hoisting-line must be used, (usually one inch in diameter,) and owing to the weight of the line and hose a number of men are required to draw up the hose, and considerable time is necessarily consumed; and in dragging the hose over the cornice and in contact with the window-sills and other projecting parts of the building it becomes worn, and hence requires to be frequently replaced.

The object of this invention is to overcome these difficulties, and to facilitate the hoisting of hose to elevated positions.

The invention consists in the portable hoist, which is hereinafter claimed, and illustrated in the accompanying drawings, in which—

Figure 1 is a view of the improved hoist,

showing its application in drawing hose to the roof of a building. Fig. 2 is a side view of the hoist; Fig. 3, a central vertical longitudinal section. Fig. 4 is a top view, and Fig. 5 is a front view, of the hoist.

55

This hoist consists of two parallel plates or side frames, A A, each having a long arm or branch, *a*, and a short arm or branch, *b*. These arms or branches *a* and *b* extend at substantially right angles to each other, and one of them, preferably the shorter one, is shaped to form a pointed hook, B, the hook pointing in the line of the longer arm. The general shape of each plate or frame, it will be seen, is that of a hook or grapnel. The two plates or frames 65 are connected together by means of cross bars or rods C C, which extend between the plates near the ends of the branches *a* and *b*. Each of these rods is shouldered near each end, as at *c*, against which shoulders the inner faces 70 of the plates or frames rest, whereby the plates are held at a fixed distance apart. The rods have screw-threaded ends *d*, which extend through suitable apertures in the plates or frames, and upon them, outside of the plates, 75 nuts *e* are screwed to hold the plates or frames together. Extending between the two plates or frames between the two branches, and near and on either side of the angle formed by them, are two other rods or shafts, D D, which are 80 preferably shouldered and screw-threaded, as in the case of the rods C C, and screwed to the plates or frames by similar nuts *e*. These rods serve as shafts, upon which are rotatively mounted two anti-friction cylinders or rollers, 85 E E. These cylinders or rollers are slightly less in length than the distance between the plates A A, so that they may freely rotate upon the shafts. Each cylinder or roller is also slightly concaved on its surface, having its 90 greatest diameter at the ends and its least diameter at the center. The cylinders or rollers are made thus concave in order that the hose which is drawn over them may be kept at the center and away from the side plates as much 95 as possible. The side plates, A A, extend far enough beyond the surfaces of the cylinders to furnish sufficient guides for the hose and to prevent it from slipping off from the cylinders, and they are flared slightly outward in 100

order to prevent the hose from coming in contact with their edges.

To one of the rods C C—preferably the one between the long arms a a—is pivotally hung 5 a swinging bail, F, to which is permanently attached a securing or holding line, G, of, say, fifteen or twenty feet in length. The hoist itself may also serve as a reel upon which the roof-line is wound when not in use.

10 In using this hoist in the case of hoisting hose upon a roof, it is placed as shown in Fig. 1. The hoist is first carried upon the roof, and the roof-line unwound therefrom. The hoist is then placed with the long arms upon the 15 roof and the short hooked arms holding beneath the cornice. The securing-line is then passed around some permanent object upon the roof and one end of the roof-line is thrown to the ground, where it is attached to the hose.

20 The roof-line is then drawn up over the anti-friction cylinders or rollers. When the hoist is in position on the roof, the cylinder or roller mounted in the short arm extends out beyond the cornice, so that in drawing up the hose it 25 will swing free from the window-sills and other projections on the roof, and the cylinder or roller mounted in the long arms being above the cornice the hose and roof-line are thereby prevented from coming in contact with the cornice 30 or roof. These cylinders or rollers thus serve to protect the hose and line from wear, and also render it much easier to draw up the hose, so that only a few men are required to manage the hose. At the same time a much lighter 35 roof-line may be used, since there is so much less strain upon it. This decreased weight of line, together with the absence of the usual reel, fully counterbalances the weight of the hoist, so that no additional burden is placed 40 upon the firemen in the carrying of the hoist.

The connection of the securing-line to the hoist is important, since it insures its constant

attachment thereto, and the line thus serves as a means for securing the hoist in position whenever it is necessary to do so.

The use of the hoist in other positions will 45 be obvious. When placed on a ladder for drawing hose up thereon, the hooks B B will be placed upon one round of the ladder with the long arms hanging down.

The hoist is preferably made entirely of metal, both for the sake of strength and to render it indestructible by fire. Two cylinders or rollers are used, since each may thereby be comparatively small, and the two may include 50 a large enough radius to carry the hose clear beyond the cornice on both sides.

This hoist may be used equally well for hoisting other things besides hose, and will be found convenient in hoisting the fire-ladders as well 55 as the hose.

I am aware that portable hose-hoists having side plates or frames hook-shaped to adapt them for attachment to roof-cornices, anti-friction rollers being mounted in said side plates, 60 over which the hose is drawn, are not new; and I am also aware that it is not new to provide a permanent hose-conveying device to a building, in which rollers are mounted between projecting side plates. I therefore make 65 no claim to embrace or include such devices.

I claim as my invention—

In a hose-hoist, two plates or frames connected together, in combination with an anti-friction roller or rollers mounted between said 75 plates, said plates or frames extending beyond the peripheries of said rollers, and being flared outward, substantially as set forth.

In testimony whereof I affix my signature in presence of two witnesses.

JOHN J. BRESNAN.
